(57) CLAIM

The ornamental design for a Flip-top Lid as shown and described.

DESCRIPTION

DESCRIPTION OF THE FIGURES

FIG. 1 is a perspective view of a Flip-top Lid, showing my new design, in a closed position, and in an environment of use with an exemplary tumbler;

FIG. 2 is a front view thereof, with the exemplary tumbler removed;

FIG. 3 is a rear view thereof;

FIG. 4 is a right side view thereof;

FIG. 5 is a left side view thereof;

FIG. 6 is a top view thereof;

FIG. 7 is a bottom view thereof; and

FIG. 8 is a perspective view thereof, in an open position, and in an environment of use with an exemplary tumbler.

The Flip-top Lid is semi-transparent.

The surface shading and contour lines shown in the drawings represent the three-dimensional character and contour of the article, and are not intended to illustrate material, surface ornamentation or surface decoration.

The broken lines of FIGS. 1 and 8 depicting environment of an exemplary tumbler that form no part of the claimed design. The broken lines of FIG. 7 depict portions of the Flip-top Lid that form no part of the claimed design.
